FOREIGN PATENT DOCUMENTS

1253019 12/1960 (FR) .

FIG. 1 is a top perspective view of a pan corner showing my new design;
 FIG. 2 is a top plan view, the bottom plan view being a mirror image thereof;
 FIG. 3 is a front elevational view;
 FIG. 4 is an auxiliary elevational view taken along lines 4—4 of FIG. 2;
 FIG. 5 is a right side elevational view thereof;
 FIG. 6 is a sectional view taken along line 6—6 of FIG. 2;
 FIG. 7 is a top perspective view of a second embodiment of FIGS. 1-6;
 FIG. 8 is a top plan view of the second embodiment; the bottom plan view being a mirror image thereof;
 FIG. 9 is a front elevational view of the second embodiment;
 FIG. 10 is an auxiliary elevational view of the second embodiment taken along lines 10—10 of FIG. 8;
 FIG. 11 is a right side elevational view of the second embodiment; and,
 FIG. 12 is a sectional view of the second embodiment taken along lines 12—12 of FIG. 8.
 One of the broken lines in FIGS. 1-5 and 7-11 indicates indeterminate length while the other broken lines are for illustrative purposes only and forms no part of the claimed design.
